ACOUSTIC BAFFLE CONSTRUCTION

Wilbur T. Harris, Southbury, Conn., assignor to The Harris Transducer Corporation, Woodbury, Conn., a corporation of Connecticut

Application April 28, 1954, Serial No. 426,219

14 Claims. (Cl. 181—33)

My invention relates to an acoustic-baffle construction, as of the sort which may be employed in underwater-sound transducer installations where it is necessary to shield a transducer from directional noise originating outside the transducer or to reflect sound originating from a particular direction.

It is an object of the invention to provide an improved baffle construction.

It is another object to provide a baffle construction lending itself to flexibly adapted use, depending upon a multitude of installation requirements.

It is a further object to provide an efficient sound-absorbing or reflecting baffle for prolonged underwater use and not susceptible to time-deterioration as occasioned by water absorption with prolonged underwater exposure.

Other objects and various further features of novelty and invention will be pointed out or will become apparent to those skilled in the art from a reading of the following specification in conjunction with the following drawings. In said drawings, which show, for illustrative purposes only, preferred forms of the invention:

Fig. 1 is a partly broken, vertical sectional view of a baffle construction embodying features of the invention;

Fig. 2 is a perspective view on a reduced scale, showing the sound-absorbent or reflecting face of the baffle of Fig. 1; and

Figs. 3 and 4 are fragmentary sectional views illustrating modifications.

Briefly stated, the invention contemplates means for eliminating of the time-deterioration factor which has previously characterized the use of sound-absorbent or reflecting materials, such as air-filled rubber, in underwater-sound baffles. For large-area baffles, it has been customary to bond rubber or rubber-like material to the exposed surface of the body of sound-absorbent or reflecting material, but, unless excessive thicknesses of such material are applied, the time-deterioration factor (occasioned by slow diffusion of any air from the body into the surrounding water medium) substantially impairs performance. I have discovered that the time-deterioration factor can be eliminated without employing excessive thicknesses of rubber or rubber-like material, and for this purpose I show acoustically transparent metal membranes bonded continuously over the exposed baffle surface and sealed by impermeable means over the continuous peripheral extent of the membrane and of the body.

Referring to Figs. 1 and 2 of the drawings, my invention is shown in application to a baffle contained within a rigid frame 10, defining a central opening for containing the absorbent or reflecting body 11 of the baffle. The body 11 may be of any desired material having a μ c characteristic substantially lower than the acoustic impedance of water. I have indicated by sectioning that body 11 may be air-filled rubber or the like to provide substantially a planar pneumatic compliance, or that it may be loaded with metal flake, mica flake, or other relatively dense particles to provide absorptive or resistive properties. The ruggedness of the assembly may be improved by employment of a rigid

2

backing plate 12 of impermeable material, such as sheet metal, secured by bolts or rivets 13 or by welding to the frame 10. I prefer that the body 11 shall be securely bonded to the plate 12 with peripherally continuous lateral clearance, as at 14, between the body and the inner wall 15 of the opening.

To seal the other side of the baffle, I employ acoustically transparent impermeable means, and have found that a thin membrane 16 of metal, such as aluminum, copper, stainless steel, or the like, will serve the purpose. The membrane 16 is preferably bonded securely to the body of compliant or resistive material 11, and the lateral edges 18 of the membrane 16 preferably project peripherally and continuously away from the lateral confines of the body 11. For protection against rupture of the membrane 16 through mishandling, I indicate at 19 my preference for a suitably thick layer of acoustically transparent material, such as rubber or neoprene, intimately bonded to the outer surface of the membrane 16, and preferably co-extensive therewith.

In order to seal the lateral edges of the baffle, I so form the lateral confines of the membrane 16 that edges 18 project short of the inner wall 15 of the frame and so that edges 18 are offset substantially axially (or transversely) 25 in from the outer face or limit 20 of the frame. The edges 18, however, should also be axially spaced from the other limit of the frame, as defined by the back plate 12. Sealing may then be effected by potting substantially all the remaining space 14—21 in the opening of the frame 30 and thus continuously and peripherally overlapping the seal membrane 16, the body 11, and the otherwise-exposed interfit of the body 11 with the backing plate 12. The potting may suitably be any of the well-known acoustically transparent impermeable plastics, such as a polymerized epoxy composition.

In Fig. 3, I show a modification in which the body 30 of acoustically resistive or compliant material is sealed on both faces by a symmetrical employment of thin, flexible, acoustically transparent membranes 31—32. The membranes 31—32 and bonded sheathing 33 may be of the construction described at 16—19 in Fig. 1. Thus, peripherally projecting membrane edges 34 may be axially spaced from each other and from the axially outer limits 35—36 of frame means 37. A potting 38 of impermeable sealing material may complete the assembly and may overlap all exposed projections and interfits between membranes 31—32, body 30, and sheaths 33. To enhance the axial support afforded by frame means 37, I show the frame to be of channel-shaped section, with a channel groove defined by spaced walls 40—41 extending inwardly, that is, toward the body 30, and peripherally overlapping the outward projection of limits 34 of the impermeable membranes.

In Fig. 4, I show a modification in which resistive and 55 compliant properties are embodied in a construction similar to Fig. 1 but through employment of separate layers 50—51 of resistive and compliant materials. The resistive layer 50 may be pellet-filled rubber or the like, and the compliant layer 51 may be air-cell rubber. Otherwise, the construction may be the same as in Fig. 1, and corresponding reference characters are therefore employed.

It will be seen that I have described an improved baffle construction featuring complete impermeable sealing of acoustically compliant or resistive materials, so as to assure no loss of these properties by reason of air or water seepage during prolonged underwater exposure. This feature is achieved without employment of excessively bulky sheathing. The construction is rugged and lends itself to adaptation to meet a wide variety of specific installation requirements. In the employment of air-filled or gas-filled materials for bodies 11—30, my constructions provide nearly perfect reflectors for sound from either direction,

except at frequencies below which they become acoustically transparent; they are essentially low-pass filters, with the cut-off frequency depth-dependent but not time-dependent.

While I have described the invention in detail for the preferred forms shown, it will be understood that modifications may be made within the scope of the invention as defined in the claims which follow.

I claim:

1. A baffle comprising a rigid frame having an opening therein and defining a baffle area in said opening, a body of acoustic material within said opening and spaced from the inner edges of said frame, said acoustic material having an impedance lower than that of water, impermeable sheaths on both sides of said body, one of said sheaths being acoustically substantially transparent, and a potting of impermeable sealing material overlapping the edges of said transparent sheath and of said body and filling the space between said body and said frame and said other sheath.

2. A baffle comprising a relatively stiff backing plate, a body of acoustic material supported on one side of said plate and of lesser extent than said plate whereby peripheral parts of said plate project outwardly of said body, an acoustically transparent impermeable sheath over the exposed side of said body and projecting peripherally over the lateral limits of said body, and impermeable sealing means in intimate sealing relation with said body and with peripherally projecting parts of said plate and said sheath.

3. A baffle according to claim 2, in which said sheath comprises a thin flexible metal sheet.

4. A baffle according to claim 2, in which said sheath comprises an outer layer of rubber-like material and an inner impermeable membrane.

5. A baffle according to claim 2, in which the impedance of said material includes a substantial compliance component.

6. A baffle according to claim 2, in which the impedance of said material includes a substantial resistance component.

7. In a baffle, a body of acoustic material, two thin metal flexible membranes bonded to opposite sides of said material and projecting peripherally of the lateral confines of said body, rigid means peripherally framing said body and membranes, and impermeable sealing material overlapping the peripherally projecting ends of said membranes and filling the space therebetween and bonded to said rigid means.

8. A baffle comprising an open frame of channel-shaped section with a channel groove facing inwardly, a body of

acoustic material in the opening of said frame, two impermeable flexible sheaths intimately contacting opposite sides of said body and projecting peripherally of the lateral confines of said body, said peripheral projections extending into the channel groove, and a filling of impermeable plastic sealing material filling the channel and peripherally sealing the projecting edges of said membranes and the exposed lateral edges of said body.

9. A baffle comprising a body with a layer of compliant material and a layer of resistive material, means sheathing both sides of said body, said means including acoustically transparent impermeable means on one side of said body, and an impermeable plastic filler overlapping the lateral edges of said impermeable means and covering the lateral edges of said body.

10. A baffle comprising a rigid frame having an opening therein and defining a baffle area in said opening, a resistive and compliant body in said opening and spaced from the inner edges of said frame, impermeable sheaths on both sides of said body, one of said sheaths being acoustically substantially transparent, and a potting of impermeable sealing material overlapping the edges of said transparent sheath and of said body and filling the space between said body and said frame and said other sheath.

11. A baffle according to claim 10, in which said other sheath is a sheet of metal anchored peripherally to said frame.

12. A baffle according to claim 10, in which said body comprises separate resistive and compliant layers.

13. A baffle comprising a relatively stiff metal sheet, a body of acoustic-impedance material having an impedance lower than that of water and overlying one side of said sheet, an impermeable flexible metal sheath over the exposed side of said body, and a peripheral seal of impermeable sealing material overlapping the edges of said sheath and of said body and sealed to said sheet.

14. A baffle comprising a body of acoustic-impedance material, acoustically transparent impermeable means sheathing both sides of said body, and an impermeable plastic filler overlapping the lateral edges of said impermeable means and covering the lateral edges of said body.
